UNITED STATES PATENT OFFICE.

JOSEPH C. LOCKHART, OF ATTICA, KANSAS.

LIQUID-FUEL BURNER.

1,204,288.

Specification of Letters Patent. Patented Nov. 7, 1916.

Application filed April 4, 1916. Serial No. 38,862.

To all whom it may concern:

Be it known that I, JOSEPH C. LOCKHART, a citizen of the United States, residing at Attica, in the county of Harper and State 5 of Kansas, have invented certain new and useful Improvements in Liquid-Fuel Burners; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to new and useful improvements in hydro-carbon burners and it has for its object to provide a burner of this character which will preheat the fuel 20 to the proper degree to form a gas which, when introduced into the mixing chamber together with the proper amount of air, will produce a perfect combustion, thus eliminating all smoke, such as is found in 25 burners of the ordinary type.

To these ends and to such others as the invention may pertain, the same consists in the peculiar arrangement, combination and adaptation of parts, all as will be more 30 fully hereinafter described, shown in the accompanying drawings and then specifically defined in the appended claims.

My invention is illustrated in the accompanying drawings, in which:

35 Figure 1 is a side elevation, partly in section, of my improved burner, and Fig. 2 is a bottom plan view, the pan being removed.

Reference now being had to the details of the drawings by letter, A represents the 40 burner having a top plate A' which is provided with a downwardly extending flange A² having openings A³ therein, which begin at the lower edge of said flange and terminate about half way between said edge and 45 the under side of the top plate A', and the space within the burner between the upper ends of the slots A³ and top plate A' forms a fuel preheating chamber A⁴. A pan P surrounds the lower edge of the flange A² and serves as a bottom or flash pan. 50

A fuel supply pipe B provided with a controlling valve B' is passed through the flange A² and is coiled as at B² within the upper part of the chamber A⁴ and is then 55 passed out through said flange A² and downward, and coiled as at B³ about the

outside of the flange A² at a point about midway the height of the slots A³, as shown in Fig. 1 of the drawings. Said pipe projects a short distance from the burner and 60 is bent back upon itself to form a nozzle B⁴ which projects into a mixing nipple C secured to the flange A², the opening through the nipple C communicating with the interior of the burner to permit of free passage of air and gas, said gas being controlled by a suitable valve C'.

In operation, a small quantity of fuel is ignited in the flash pan which will heat the burner and heating chamber A⁴. The fuel 70 within the coil B² will be preheated and converted into gas which will pass through the coil B³ which is in direct contact with the flame from the slots A³, which will further heat the said gas which is then directed into and through the mixing nipple C to the interior of the burner. It will thus be seen that by regulating the fuel supply valve B' and the gas valve C' a perfect 75 combustion may be obtained. 80

What I claim to be new is:

1. A hydro-carbon burner comprising a plate having a depending flange with openings leading from the lower edge of the flange and terminating short of the lower 85 side of the plate, a nipple mounted upon the flange and communicating with the space surrounded by the flange at a point between the ends of the openings, and a pipe passing through the flange at a point above the openings and coiled within the flange and passing out of the same and surrounding the flange between the ends of the openings and having its discharge end alined with the nipple. 90 95

2. A hydro-carbon burner comprising a plate having a flange depending therefrom and provided with openings leading in from its lower edge and terminating short of the plate, a pipe passing through the flange and coiled within the same and extending out through the flange and down along the outer surface thereof and passing around the flange in a plane between the ends of the openings and having a discharge end disposed toward the flange and spaced from the same, and a nipple mounted upon the flange and communicating with the interior thereof and alined with the discharge end of the pipe. 100 105

3. A hydro-carbon burner comprising a plate having a depending flange, a nipple

mounted upon the flange and communicating with the interior thereof, and a pipe passing through the flange and coiled therein, then passing through the flange and coiled about the same below the nipple and having a discharge end alined with the nipple.

In testimony whereof I hereunto affix my signature in presence of two witnesses.

JOSEPH C. LOCKHART.
